United States Patent Office

Des. 194,956
Patented Apr. 2, 1963

194,956

JUG

Clarence A. Price, Ann Arbor, and Donald P. Denhoff,
Saline, Mich., assignors to Hoover Ball and Bearing
Company, Ann Arbor, Mich., a corporation of Michigan

Filed May 24, 1961, Ser. No. 65,322

Term of patent 14 years

(Cl. D58—5)

We claim:

The ornamental design for a jug, as shown.
